UNITED STATES PATENT OFFICE.

WILLIAM LEWIS, OF UTICA, NEW YORK.

BED-SPRING.

1,262,813.

Specification of Letters Patent. Patented Apr. 16, 1918.

Application filed March 3, 1915. Serial No. 11,670.

To all whom it may concern:

Be it known that I, WILLIAM LEWIS, a citizen of the United States, and resident of Utica, in the county of Oneida, in the State 5 of New York, have invented new and useful Improvements in Bed-Springs, of which the following, taken in connection with the accompanying drawings, is a full, clear, and exact description.

10 This invention relates to certain improvements in spring beds in which the mattress, whether of woven wire or upholstering, is supported upon a system of helical springs resting on a suitable supporting frame, and 15 while the main object is to provide this class of spring beds with marginal upstanding rails for retaining the upholstered mattress in place against lateral or endwise displacement and to sustain the edges of such mattress against flattening or rolling downward, the specific object is to support the greater portions of such rails directly upon the upper ends of the coil springs so that 20 they may yield under pressure independently of the frame, but the upper ends of the springs are held in definite relation to each other.

Another object is to make these confining rails of straight and relatively heavy wire 30 as distinguished from coiled wire so as to afford greater resistance to the spreading out or displacement of the mattress laterally, and at the same time permitting them to yield vertically, as for example under the 35 pressure of a person sitting on the edge of the bed.

Other objects and uses relating to specific parts of the spring bed will be brought out in the following description.

40 In the drawings—

Figure 1 is a top plan, partly broken away, of a spring bed in which the upholstered mattress rests directly upon the upper ends of the system of helical springs.

45 Fig. 2 is an end view of the same spring bed, partly broken away.

Figs. 3 and 4 are enlarged vertical sectional views, taken, respectively, on lines 3—3, Fig. 2 and 4—4, Fig. 1.

50 Fig. 5 is an inner face view, partly in section, of the central upper portion of one side of the spring bed, showing the manner of supporting the guard rail on the upper ends of the coil springs.

55 Fig. 6 is a top plan, partly broken away,

of a modified form of spring bed, showing opposite sets of springs as supported upon the side rails of a main supporting frame and covered by a woven wire mattress, the guard rails being also shown as mounted 60 upon the upper ends of the helical springs.

Fig. 7 is a side elevation of the spring bed shown in Fig. 6, the central portion thereof being broken away.

Fig. 8 is an enlarged vertical sectional 65 view taken on line 8—8, Fig. 7, the portion of the frame to which one end of the guard rail is attached being shown in section.

In the spring bed shown in Figs. 1 to 5, inclusive, the system of helical springs as 70 —1— and —2— are mounted upon a suitable supporting frame —3— and the upper ends of the marginal series are bound or held in fixed relation by a superposed marginal frame —4—, tied to the upper ends of 75 the springs of the marginal series by suitable tie-pieces —5—.

The upper ends or convolutions of the springs —2— of the marginal series are 80 provided with extensions —6— arched upwardly and constituting resilient guards rising from the outer edges thereof some distance above the horizontal plane of the frame —4— and having at their highest points tie-pieces —7— for receiving and 85 supporting a marginal guard rail —8— which extends along both sides and across one end and part way across the opposite end or head of the frame —4— in a plane substantially parallel with, but some distance above the same for the purpose of 90 retaining an upholstered mattress on the upper ends of the springs against lateral or endwise displacement, and at the same time sustaining the edges of such mattress 95 against flattening, flattening or rolling down.

It will be noted, however, that by supporting this guard rail directly upon the arched extensions —6— of the marginal series of springs and independently of the 100 underlying frame which ties the upper ends of said springs to each other, it permits a limited vertical yielding movement of the guard rail, and particularly the longitudinal sides thereof where pressure is most often brought to bear by persons sitting upon the edge of the mattress, and by making this guard rail of a straight piece of wire as distinguished from coiled wire, it 105 is evident that it is less liable to be stretched 110

out of shape and is, therefore, more permanent and durable in the performance of its function of holding the mattress against shifting on the springs.

- 5 This particular form of guard rail is preferably made of a single piece of wire having its ends extended from the opposite sides part way across one end, as the head end, of the bed to form end brace-rails 10'— which are depressed to the plane of the frame —4— and are secured thereto by clips —9—, the remaining portions of the guard rail extending along the sides and around the foot of the bed.
- 15 This yielding action of the guard rail is made more apparent upon reference to Fig. 5, in which it will be seen that the upwardly arched portions —6— of the helical springs —2— rise from portions of the underlying 20 convolutions of said springs some distance from the points of attachment of said underlying convolutions to the marginal frame —4—, thus not only producing the resiliency afforded by the arches —6—, but also 25 that afforded by the portions of the underlying convolutions of the spring along the sides of the bed at opposite sides of the clip —5—, the adjacent sides of the upper ends 30 of the helical side springs —2— at their junction with the spring arches —6— being sufficiently close to be tied together by tie-pieces —10— to additionally hold the upper 35 ends of said helical springs in definite relation to each other, which together with the clips —5— and —7—, serve to hold the guard rail —8— against lateral or endwise movement.

The ends of this guard rail are preferably bent downwardly at —11—, Fig. 3, to prevent 40 their accidental displacement from the clips —9—.

In Figs. 6, 7 and 8, I have shown an iron frame —3'— and opposite sets of helical springs —2'— mounted on the longitudinal 45 sides of the frame —3'— and rising therefrom.

The springs —2'— of each set carry at their upper ends a tie-frame —4'— secured thereto by clips —5'— for holding the upper 50 ends of such springs in definite relation and also serving to transmit vertical motion from one to the other, particularly when pressure is applied upon any part of the tie-frame.

55 A woven wire mattress —a— is stretched across and upon the upper faces of the tie-frames —4— and fastened at its ends to angle plates —12— on the opposite ends of the main supporting frame —3'—.

60 The springs —2'— of each set are also provided with upwardly arched extensions —6'— projecting some distance above the horizontal plane of the tie-frame —4'— and woven wire mattress —a—, as shown 65 more clearly in Fig. 7, for supporting at

their highest points opposite lengthwise guard rails 8'— performing the same functions as the guard rail —8—, as shown in Figs. 1 to 5, inclusive, said guard rails being fastened to the highest points of their 70 respective spring arches —6'— by clips —7—.

Each guard rail extends the entire length of the main supporting frame —3— and has its opposite ends deflected laterally and 75 downwardly partially across and above the ends of the main supporting frame —3'—, forming suitable feet —13—, which rest upon the upper faces of the end plates —12—, and having their terminal ends 80 passed through said plates and fastened thereto by nuts or shoulders —14— to firmly hold the rails in operative position.

It will be observed, however, that the ends of the spring arches —6'— are united directly to the upper ends of the helical springs —2'— some distance from and at opposite sides of the clips —5'— so as to allow the guard rail —8'— to yield downwardly under pressure independently of the frame —4'— in substantially the same manner as described for the guard rail —8—, in Figs. 1 to 5, inclusive.

The important feature, therefore, of my invention is the supporting of the guard rails directly upon the upper ends of the outer helical springs so as to yield independently of the frame which ties the upper ends of the springs against lateral displacement, thus affording a comparatively indestructible and permanently confining rail for the upholstered mattress, not only against shifting movement upon the helical springs, but also sustaining the edges of such mattress against flattening or rolling 105 over the edges of the marginal springs or tie-frames which connect them.

What I claim is:

1. In a spring bed, a system of coil springs and underlying supports therefor, a 110 marginal frame surrounding the upper ends of the marginal series of springs and attached thereto, a guard rail extending along one of the longitudinal sides of the bed above the corresponding side of the marginal frame, means for supporting said guard rail, and a brace-rail connecting the guard-rail to one of the end bars of the marginal frame.

2. In a spring bed, a system of helical springs and underlying supports therefor and a marginal frame extending around the upper ends of the marginal series of springs and attached thereto, in combination with guard rails extending along opposite sides of the bed above the corresponding sides of the frame, connections between the guard rails and adjacent springs for supporting said guard rails and brace rails connecting the guard rails at one end to the correspond- 120 125 130

ing end of the marginal frame some distance from the sides thereof.

3. In a spring seat or bed, a system of upright coil springs and suitable supporting means therefor, a marginal frame extending around the outer rows of said springs and attached to the upper ends thereof the springs of the outer rows being provided with upwardly extending loops, and guard

rails attached to said loops and to the marginal frame independently of said loops.

In witness whereof I have hereunto set my hand this 27th day of February, 1915.

WILLIAM LEWIS.
